UNITED STATES PATENT OFFICE.

JAMES MONROE BROWN, OF MANSFIELD, OHIO, ASSIGNOR TO THE AULTMAN & TAYLOR MACHINERY COMPANY, OF MANSFIELD, OHIO, A CORPORATION OF OHIO.

TUBE-EXPANDER.

SPECIFICATION forming part of Letters Patent No. 787,269, dated April 11, 1905.

Application filed July 19, 1904. Serial No. 217,168.

To all whom it may concern:

Be it known that I, JAMES MONROE BROWN, of Mansfield, in the county of Richland and State of Ohio, have invented a new and useful 5 Tube-Expander, of which the following is a full, clear, and exact description, reference being had to the accompanying drawings, forming part of this specification, in which—

Figure 1 is a sectional side elevation showing my expander in position. Fig. 2 is a perspective view of the rollers with the cage indicated in dotted lines, and Fig. 3 is a cross-section on the line III III of Fig. 1 looking toward the left.

15 My invention relates to the class of tube-expanders, and is designed to provide a tool of this character by which the tube can be expanded against the tube-seat and at the same time its outer end exterior to the tube-plate 20 can be swelled or forced outwardly to fix the tube in position.

In the drawings, in which I show a preferred form of my invention, 2 represents a cylindrical cage of steel, preferably having its 25 rear portion 3 reduced in size and provided with external screw-threads. The walls of the cylindrical body are cut away in concave form to provide recesses for the reception of the expanding-rollers. In the form shown I 30 have provided three such recesses, though any desirable number of recesses and sets of rollers may be used. Into one of these recesses I slip a longer roller 4, which fits loosely therein, and into the other recesses I drop a short roller or disk 5 and a roller 6, which is 35 preferably of such a length that the roller 6 and disk 5 are together of about the same length as the roller 4. The roller or disk 5 is preferably formed with a curved or oval edge, 40 as shown—that is, its diameter is greater at the center than at its ends. This avoids a shearing action upon the tube at the edge of the tube-plate. These rollers may be secured 45 in the cage against endwise displacement by the cap-plate 7, secured by cap-bolts 8, screwed into the cage-body between its recesses.

Around the threaded portion 3 I secure the split nut or internally-threaded sleeve 9. This

may be made in two parts held by a ring 10, having a pin 11, which slips in through a 50 groove 12 into an annular groove 13, cut in the halves of the split sleeve. The front face of this sleeve fits against the back end of the cage-body and is provided with arc-shaped flanges 14, formed one half on each half of 55 the nut and extending around the rear portion of the cage-body.

In using the expander the tube 15 is slipped within the circular seat in the tube-plate 16, the expander is inserted, a taper-mandrel 17 60 is forced in through the central hole in the expander, and the expander is revolved in the usual manner, while the mandrel is forced in. During this operation the longer roller 4, in conjunction with the shorter rollers 6, acts to 65 expand the tube against the tube-seat. At the same time the disks 5, being of slightly-larger diameter than the rollers 4 and 6, act to force out the end portion 18 of the tube, as shown in Fig. 1, thus fixing the tube in 70 place. During this action the single long roller prevents the formation of a ridge on the tube between the rollers 5 and 6, which would form if three sets of similar character were used. By causing the longer roller to 75 operate across the abutting line of the roller and disk I prevent the cracking or cutting of the tube at this point against the outer edge of the tube-seat. The disks being independent are forced out to give the end flare without expanding the tube against the tube-seat with any greater pressure than in the ordinary practice of expanding, this being aided by the curved or inclined faces of the disks.

The advantages of my invention result from 85 the simultaneous forcing of the tube against its seat and flaring its outer end beyond the tube-plate, also from the use of the longer roller, which prevents any ridge formation, and from the quickness and ease of operation 90 and the preventing of injury to the tube.

The use of the independent short rollers or disks 5 allows the rollers 6 to be forced out independently of them without affecting the flaring action of these disks. The incline or 95 curve on the disk gives a proper flaring ac-

tion without forcing the tube against the seat so hard as to give a shearing action. The flare is preferably made about one-fourth inch from the tube-seat.

5 The number of rollers may be varied, as well as the cage structure, the shape and size of the rollers, and other variations may be made without departing from my invention.

I claim—

- 10 1. A tube-expander having a cage, a pair of rollers in the cage abutting end to end, one of them being arranged to extend within the tube-seat and the other to flare the tube end outwardly, and another longer roller also supported in said cage and operating across the abutting line of said first rollers; substantially as described.
- 15 2. A tube-expander having a pair of rollers or disks in endwise alinement and lying together, one of them being longer than the other, and another longer roller supported at another point in the circle of the tube-ex-

pander and operating across the abutting line of said first rollers; substantially as described.

3. A tube-expander having a short roller, 25 and a disk with a rounded or oval edge fitting together in endwise alinement, and another longer cylindrical roller supported in the cage at another point around the circumference and operating across the abutting line of said 30 first rollers; substantially as described.

4. A tube-expander having shorter rollers arranged end to end and a longer roller at another point in the cage and operating across the abutting line of said first rollers, all said 35 rollers being stemless and held by portions of the cage fitting against their curved surfaces; substantially as described.

In testimony whereof I have hereunto set my hand.

JAMES MONROE BROWN.
